(57) **CLAIM**

The ornamental design for a projection screen, as shown and described.

DESCRIPTION

FIG. 1 is a front perspective view of a projection screen design showing my new design.

FIG. 2 is a rear perspective view of a projection screen.

FIG. 3 is a front view of a projection screen.

FIG. 4 is a rear view of a projection screen.

FIG. 5 is a left side view of a projection screen.

FIG. 6 is a right side view of a projection screen.

FIG. 7 is a top view of a projection screen.

FIG. 8 is a bottom view of a projection screen; and,

FIG. 9 is an enlarged view of the projection screen taken

from the circle part in FIG. 8.

Any shading and cross-hatching are not features of the design but are utilized to illustrate the surface contours of the projection screen design in the drawings.

The dash dot dash lines represents the boundary of an enlarged view and form no part of the claimed design. The broken lines in the drawings depict portions of the projection screen that form no part of the claimed design.
